[57] CLAIM

The ornamental design for a ventilated toilet seat, as shown and described.

DESCRIPTION

FIG. 1 is an exploded perspective view taken from the top, front and right side of a ventilated toilet seat showing my new design;

FIG. 2 is a front elevational view thereof;

FIG. 3 is a rear elevational view thereof;

FIG. 4 is a right side elevational view thereof, the left side being a mirror image of the right side;

FIG. 5 is a top plan view thereof; and,

FIG. 6 is a bottom view thereof.

FIG. 2

FIG. 3

FIG. 4

FIG. 5

FIG. 6
